UNITED STATES PATENT OFFICE

HOWARD WENTWORTH OTIS, OF NORTH WEYMOUTH, MASSACHUSETTS

SPRING OILER

Application filed July 11, 1925. Serial No. 42,916.

This invention relates to a device to be carried by the spring of a motor vehicle or the like, to supply the leaves of the spring with a lubricant at all times to enhance the riding qualities of the vehicle equipped with the spring.

Another important object of the invention is to provide a device of this character which may be readily and easily removed and replaced so that repairs on the device or replacement of parts thereof may be carried out with facility.

A still further object of the invention is to provide a metal casing which will be waterproof to eliminate any possibility of water finding its way to a point between the wick or felt lining of the device and the spring, to rust the spring.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of a spring equipped with lubricating devices constructed in accordance with the invention.

Figure 2 is a longitudinal sectional view through a spring boot or lubricating device.

Figure 3 is a transverse sectional view through the boot.

Referring to the drawing in detail, the device includes a body portion indicated by the reference character 5 which is formed preferably of sheet metal, the same being of a width slightly greater than the width of the spring on which it is positioned so that the body portion may be held in position by means of its frictional contact with the wick of the device and the side edges of the spring.

Forming a part of the body portion are the end flanges 6, and lateral flanges 7 the lateral flanges 7 being of widths to extend appreciable distances over the side edges of the spring to which the boot is applied. The end

flanges 6 are relatively narrow, but are of widths to contact with the upper surfaces of the spring and hold the wick, which is indicated at 8 against movement longitudinally of the body portion. This wick is formed preferably of felt and as shown by Figure 3 of the drawing, embraces the side edges and upper surface of the spring to carry the lubricant to points between the leaves of the spring to lubricate them.

The reference character 9 indicates a reservoir that is supported by the upper surface of the boot or lubricator and has communication with the interior of the body portion 5 through the opening 10, which opening is closed by the wick 8 that receives oil by absorption therethrough.

The reservoir is provided with a filling opening 11 through which oil may be supplied to the reservoir. The securing device forming a part of the invention is in the form of a rod 12 having eyes 13 at its ends, which eyes accommodate the lower ends of the coiled springs 14, the upper ends thereof being formed into hooks 15 that pass into openings formed in the body portion 5 as shown by Figure 3 of the drawing.

In use, the rod 12 is positioned under the spring and the hook members 15 of the springs 14 are positioned in the openings of the body portion arranged adjacent thereto, thereby clamping the body portion in position.

From the foregoing it will be obvious that oil will be absorbed by the felt or wick 8, which oil will be squeezed from the felt or wick at each movement of the spring supporting the boot, with the result that the vehicle springs are thoroughly lubricated at all times.

I claim:—

A lubricator attachment for vehicle springs, including a body portion of a width greater than the width of the spring to which the body portion is applied, depending flanges formed at the sides and ends of the body portion, a wick held between the flanges, a rod having eyes at its ends positioned under the spring, spring members connected with the eyes, said spring members having

hooks at their upper ends, said hooks adapted to be positioned in openings formed in the body portion, and a reservoir on the body portion and adapted to feed oil to the wick.

5 In testimony that I claim the foregoing as my own, I have hereto affixed my signature.

HOWARD WENTWORTH OTIS.
